UNITED STATES PATENT OFFICE.

GEORGE S. HILTZ, OF NEW YORK, N. Y., ASSIGNEE TO THE STOCK QUOTATION TELEGRAPH COMPANY, OF NEW YORK, N. Y., A CORPORATION OF NEW YORK.

PRINTING-TELEGRAPH RECEIVER.

1,085,124.

Specification of Letters Patent.

Patented Jan. 27, 1914.

Application filed April 8, 1912. Serial No. 689,226.

To all whom it may concern:

Be it known that I, GEORGE S. HILTZ, a citizen of the United States, residing at New York, county of Kings, and State of New York, have invented certain new and useful Improvements in Printing-Telegraph Receivers, of which the following is a full, clear, and exact description.

This invention relates to printing telegraph receivers, and while it embraces features applicable to so called "page printers" it is designed more particularly for devices which print on a tape and which are commonly known as "stock tickers."

15 The chief object of the invention is to simplify the apparatus, making it positive in operation, less liable to derangement in use, and cheaper to manufacture.

20 To this and other ends the invention consists in the novel features of construction and combinations of elements hereinafter described, and more particularly set forth in the appended claims.

25 A convenient and effective embodiment of the invention is illustrated in the accompanying drawings, in which—

Figures 1, 2, and 3 are front, side, and plan views respectively, of the complete machine. Fig. 4 is a detail front view and 30 Fig. 5 is a detail sectional side view, of the printing platen, which carries the paper strip or tape against the type wheel to receive impressions therefrom. Fig. 6 is a section substantially on line 6—6 of Fig. 1.

35 The various operative parts of the device are conveniently mounted on or between a pair of parallel frame plates 10, 11, which are themselves firmly secured to the upper portion of a cross plate 12 attached to an arm 13 extending inwardly from an annular base 14. The latter, provided with an aperture 15 through which the tape issues as fed along by the tape-feeding devices, is 40 adapted to be seated on a suitable pedestal and to support the usual dome-shaped glass cover, neither of which is shown herein.

45 The type wheel consists of two disks 16, 17, with the desired characters on their peripheries, 16 bearing letters and 17 bearing numerals and the usual fractions. These disks are mounted on a shaft 18 journaled in the side frame 10 and a bracket 19 at the top of frame 11, the type wheel being between the bracket and the frame, as shown 50 in Fig. 1. At the end of the shaft adja-

cent to the frame 10, at the left of the machine as viewed from the front, is a pinion 20, meshing with a gear 21 loosely mounted on a transverse shaft 22, by which gear the pinion, and with it the shaft 18 and the type 55 wheel are rotated to bring a desired pair of characters to the printing position. On the side of the gear is a barrel 23 (Figs. 1 and 6), containing a coil spring 24 attached at one end to the barrel and at the other end to the shaft 22, so that by rotating the latter the spring may be tensioned to rotate the gear. For the purpose of thus winding up the spring the shaft 22 is provided with a fine-toothed ratchet wheel 25 (Figs. 1 and 6) actuated by a pawl 26 on the armature shaft 27 of an electromagnet 28. As the pawl is raised by the armature shaft the pivoted pawl-finger 29, held in engagement with the ratchet by a light spring 30, is 70 advanced, and as the pawl is depressed by the coil spring 31 after the magnet is de-energized the finger is retracted. Thus at each energization of the magnet the shaft 22 is given a slight rotary movement to tension the spring 24. During the advance of the winding pawl the ratchet and shaft are held stationary by a spring holding pawl 32 co-operating with the ratchet. On the shaft adjacent to the frame 11 is a heavy 75 fly wheel or momentum device 33, which, under the vigorous impulse of the winding pawl, serves to rotate the shaft farther than the movement of the pawl alone would do, thereby winding the spring more rapidly. 80 To prevent overwinding of the spring, which would of course have the effect of locking the parts so that the pawl 26 and armature shaft 27 could not rock, the barrel 23 is made in two parts,—an outer part 23^a fast to the gear 21, and an inner part 23^b to which the spring is attached, as shown in Fig. 6. The inner part consists of a disk 23^c fitting the part 23^b and rotatable therein and on the shaft 22, and a flange 23^d 85 to which the spring 24 is connected. On the disk is a series of blade springs 23^e engaging frictionally the inner surface of the flange 23^d. Consequently, when the spring is wound up to full tension the spring fingers 23^e simply slip on the flange 23^d. To provide a yielding connection between the pinion 20 and shaft 18 the former is mounted 90 loosely on the shaft and is connected frictionally thereto by a coil spring 20^f. 100

one end frictionally engaging the shaft and at the other end similarly engaging the pinion.

The rotation of the type wheel and the type wheel shaft, under the influence of the spring 24, to bring the desired characters to the impression point, is controlled by an electromagnetic escapement mechanism, comprising a scape wheel 35 (Figs. 1 and 6), an anchor 36, electromagnets 37, 38, and an armature composed of two armature-fingers 39, 40, of magnetic metal, mounted on a non-magnetic member 41. The armature is pivoted between the poles of a permanent magnet 42, with the forward ends of the fingers 39, 40 adjacent to the poles of the permanent magnet, so that the said fingers are polarized and are in effect permanent bar magnets. The electromagnets 37, 38 are arranged one above the other, as shown, with their poles on opposite sides of the armature-fingers and are connected in series, but the direction of the flow of current through them is such as to make their polarities always of opposite sign. Suppose, for example, that the inner or rear poles of the finger 39 are positive, and that the current is flowing in such direction through the electromagnets as to make the adjacent pole of magnet 37 negative and the corresponding pole 38 positive. The other poles of the two electromagnets being then respectively positive and negative, it will be seen that magnet 37 will attract and magnet 38 repel the armature, thereby rocking the latter upwardly. Conversely, a current impulse of opposite direction will, by reversing the polarity of the electromagnets while the polarity of the fingers 39, 40 remains constant, rock the armature downwardly. An exceedingly quick actuation of the anchor, which is fixed on the non-magnetic connecting member 41, is thereby obtained, and the operation also requires very little current. This rocking of the armature releases the anchor pallets alternately from the scape wheel and so permits the type wheel shaft 18 to rotate step by step until the desired pair of characters are at the impression point. To limit the movement of the armature and the anchor in each direction a pair of adjustable screw stops 43, 44 are provided, to coöperate with a lug 45 extending forwardly from the connecting member 41 which supports the anchor and the armature fingers.

The tape 46 on which the impressions are made is wound on a reel shown diagrammatically at 47 at the base of the machine, and, passing over a spring guide 48, is fed forwardly between the type wheel and the platen 49 (Figs. 1 and 2) by means of the toothed feed wheel 50 coöoperating with a cramp disk 51 mounted on a spring arm 52 and having on its periphery a shallow

groove into which the teeth of the feed wheel may project. In front of the platen the tape passes downwardly over a guide 53, and thence out through the opening 15 in the base 14. The feed wheel 50 is mounted on a short shaft or stem 54, journaled in the side frame 11 and provided with a ratchet 55 actuated by a pawl 56 pivoted on the forward end of an arm 57 which is rigidly but adjustably mounted on the armature shaft 27. The pawl 56 being held in engagement with the ratchet by a light coil spring 58 it will be seen that when the magnet 28 is energized, thereby rocking shaft 27 clockwise as viewed in Fig. 6, the pawl will be retracted over a tooth on the ratchet and that when the magnet is de-energized the reverse rocking of the shaft 27 by the coil spring 31 will advance the pawl, thus giving the feed wheel 50 a slight movement of rotation sufficient to feed the tape forward a distance equal to one letter-space. During retraction of the feed pawl the feed wheel is held stationary by a spring holding pawl 59.

The type wheel is inked (Figs. 1 and 2) by an inking roller 60 rotatably mounted in a yoke 61 pivoted to the side frame 11 so that the roller bears by gravity on the type wheel, the rear end of the yoke partially counter-balancing the weight of the roller and thereby lightening the pressure thereof on the type wheel. The face of the inking roller is of soft spongy rubber or equivalent material and is inked by periodical contact with fibrous brushes 62 (Fig. 3) drawing ink by capillary attraction from a tubular ink reservoir 63 pivoted on the frame 11. On the reservoir is a light arm 64 extending laterally and having a finger 65 adjacent and parallel to the fly-wheel 33. The latter is provided with a lug 66 which, once in each revolution, engages the finger and swings the same and the ink reservoir forward, bringing the brushes 62 into contact with the inking roller and applying ink thereto. When the lug passes the finger the reservoir drops back by gravity, withdrawing the inking brushes from contact with the roller.

The printing is effected by the platen 49 carrying the tape against the inked type; and inasmuch as the characters on the two type wheel disks are in axial register it will be seen that if both sides of the tape are carried against the type wheel by the platen the tape would receive two impressions, one from each disk. In order to prevent this, so that only one impression can be made at a time the platen, which is mounted on the arm 57 and hence is actuated by the magnet 28, is constructed as follows: The body 67 of the platen (Figs. 4 and 5) is tubular and is rectangular in cross section, and contains a horizontally reciprocating cam member 68

of inverted V form. Slidable vertically in the body 67 are two small plates 69, 70, one below each type wheel disk, provided with oppositely inclined slots in which the oppositely inclined portions of the cam member 68 are fitted. In the position shown in Fig. 4 the plate 69 is elevated; but, as will be readily understood, if the cam member is moved to the right it will depress the plate 69 and raise plate 70. It will also be seen that with plate 69 elevated the left-hand portion of the tape will be brought against the type disk 16 when the platen is raised, and that with the plate 70 raised the right-hand portion of the tape will be carried against the disk 17. In each case the portion which should not reach the adjacent type-disk is held away from the same by an arm 71 extending from a support 72, on which it is adjustably mounted, to a point between the type disks and above and beyond the space between the printing plates 69, 70.

For the purpose of shifting the cam member 68 to elevate and depress the platen-plates 69, 70, the leftwardly extended end of the member is provided with two pins 73, engaging between them a finger 74 extending downwardly from a shifting device 75 fulcrumed on the arm 57. This device is in the form of a lever having arms 76, 77, and having at its fulcrum an inverted V-shaped cam lug 78, engageable on one side or another by a V-shaped shifting spring 79. If the arm 76 be depressed from the position shown in Fig. 4, it is apparent that the instant the cam lug 78 passes the lower edge of the spring the latter will immediately continue the movement of the lever, instantly throwing the cam member 68 to the right. Similarly, depression of arm 77 causes instant movement of the cam member toward the left. The use of a V-shaped shifting spring insures that the lever 75 will always be fully actuated and will at no time remain in a horizontal or half-way position. The spring also holds the lever in position and prevents the pressure of the printing plates against the type disks from causing depression of the plate which happens to be in operation at the time. The leftward movement of the cam member 68 is limited by an adjustable stop at the outer end thereof, coöperating with the outer face of the body portion 67, said stop comprising a small eccentric disk 68^a held in adjusted position by a screw 68^b.

The movement of the shifting lever 75 is initiated by one or the other of two fingers 80, 81, extending radially in opposite directions from the type wheel shaft 18. When it is desired to print letters on the tape the shaft is rotated by releasing the scape wheel the proper number of times to bring the finger 80 directly over the arm 77 of the shift-

ing lever 75. Now when the platen is raised by the magnet 28 the arm 77 strikes the finger 80 and is depressed, thereby shifting the lever and causing the cam member to be thrown to the left. Similarly, when the finger 81 is brought over the arm 76 the cam member will be shifted to the right and impressions will then be taken from the type disk 17. Blank spaces may be left on the type disks, to reach the impression point 75 when the corresponding finger 80 or 81 is in operative position, but to economize space on the disks it is preferred to provide each disk with a useful character at such points, as for example a period or other mark of 80 punctuation. By providing the same character on both disks the character may be printed from either disk without causing the cam member 68 to be actuated.

The downward movement of the printing 85 arm 57 is limited by a stop 82 on the frame 11, and its upward movement is limited by a pivotally adjustable stop 83 on the same frame.

The unison device is of the type illustrated 90 in my copending application Serial No. 685,145, and comprises a short piece of wire 84, (Figs. 1 and 3), coiled helically on the type wheel shaft 18 in the manner of a screw thread, engaging the lower edge of an arm 85 mounted to swing vertically in a stud 86 which is itself capable of slight rotary movement in the arm 87 on which it is carried. As the shaft 18 rotates the wire 84 carries the arm 85 to the left until eventually a leftwardly extending pin 88 on said arm is brought into the path of a finger 89 on the shaft, formed by the projecting end of the wire 84. This brings the receiver into unison with the distant transmitter, and further 100 rotation of the type wheel is prevented by the finger 88 until an impression is taken from the type wheel. When this operation takes place an arm 90, consisting of a wire coiled tightly around the armature shaft 27 105 and having its free end bent laterally under the arm 85, raises the latter out of the engagement with the thread 84 and permits the coil spring 91 to swing it back to its initial position with the finger 88 out of the 110 path of the stem 89. Of course this return of the arm 85 to its rightward or initial position occurs whenever the armature 92 of magnet 28 is depressed by the magnet, regardless of whether or not the finger 88 and 115 89 are in engagement; but where the printing operation is performed frequently enough to keep the two fingers from engagement there is small likelihood of the transmitter and the receiver being out of 120 unison. In practice the sending operator can, from time to time, bring the two into 125 unison by rotating the type wheel shaft, without printing, far enough to insure engagement of the unison fingers. 130

The apparatus is a "one wire" machine, that is, it operates on a single transmission circuit, and the three electromagnets are in series. Any suitable transmitter may be employed which is capable of sending current impulses of alternating polarity and of prolonging at will any impulse of either polarity. The magnets 37 and 38 have a small time constant and are therefore energizable by the short current impulses, thereby quickly bringing the desired characters on the type disks to the impression point. The magnet 28 is also energizable by current in either direction, but has a larger time constant and hence is not sufficiently energized, by any of the alternating impulses which cause rotation of the type wheel, to actuate the armature 92 and the other mechanisms connected to the shaft 27. When, however, the sending operator desires to print, the final impulse required to set the type wheel is simply prolonged, thereby giving the magnet 28 time to be fully energized. The armature 92 is thus depressed.

Practical use of the apparatus herein specifically illustrated and described has shown it to be satisfactory for the purpose for which it is designed, and it is the preferred form of the invention; but to persons skilled in the art it will be apparent that the invention can be embodied in other forms without departure from its proper spirit and scope as defined by the following claims.

I claim:

1. In a printing telegraph receiver, the combination of a pair of type disks in axial alinement, and rotatable to bring desired characters to the impression point; a printing platen movable toward and from the type disks, comprising a body, a pair of members carried by the body and shiftable therein toward and from the type disks, and means carried by the body and movable relatively to both said members to shift either member toward and the other from the type disks; and mechanism for actuating said means, operated by movement of the platen toward the type disks.

2. In a printing telegraph receiver, the combination of a rotary type wheel having a plurality of circular rows of characters on its periphery; a platen movable toward and from the type wheel, comprising a body, a plurality of impression members carried by the body and shiftable therein toward and from the type wheel, and means carried by the body and movable relatively to all said members to shift any one of said members toward and the rest from the type wheel; and mechanism actuated by movement of the platen toward the type wheel to operate said means.

3. In a printing telegraph receiver, in combination, a rotary type wheel having two circular rows of characters on its periphery;

a platen movable toward and from the type wheel, comprising a body, a pair of impression members carried by the body and shiftable therein toward and from the type wheel, and a transversely movable cam carried by the body and coöperating with the shiftable members to shift either of them toward and the other from the type wheel; and means actuated by movement of the platen toward the type wheel to move said cam.

4. In a printing telegraph receiver, in combination, a rotary type wheel having two rows of characters on its periphery; a platen movable toward and from the type wheel, comprising a body, a pair of impression members carried by the body and shiftable therein toward and from the type wheel, and a sliding V-shaped cam carried by the body and coöperating with said members to shift either of them toward and the other from the type wheel; and means whereby movement of the platen toward the type wheel may actuate said cam.

5. In a printing telegraph receiver, a printing platen comprising a body, a pair of impression members carried by the body and shiftable therein in parallel paths, and a V-shaped cam slidable transversely of said members and coöperating therewith to shift the same simultaneously but in opposite directions.

6. In a printing telegraph receiver, a printing platen comprising a flat, rectangular body, a pair of impression plates carried thereby and shiftable therein in parallel paths, and a cam of inverted-V form slidable transversely of said plates and coöperating therewith to shift the same simultaneously but in opposite directions.

7. In a printing telegraph receiver, in combination, a type wheel having a plurality of circular rows of characters and rotatable to bring desired characters to the impression point; a platen comprising a member movable toward and from the type wheel and printing plates, one for each row of characters, carried by said member and slidably mounted therein so as to be adjustable toward and from the type wheel; a V-shaped cam member slidable transversely in said member and coöperating with the printing plates to adjust the same; an oscillatory arm to reciprocate the cam member; and means for actuating the arm, comprising a lever carried by the arm, a finger movable into the path of the lever as the same moves with the platen, to initiate the movement of the arm, and a spring associated with the lever to complete the movement and hold the lever at the end of the movement.

8. In a printing telegraph receiver, in combination, a type wheel; a spring associated with the type wheel to rotate the same; a shaft connected with the spring, and rota-

table to tension the spring; an inking roller coöperating with the type wheel to ink the same; a movable inking device for applying ink to the roller; and means actuated by said shaft to actuate the inking device.

9. In a printing telegraph receiver, in combination, a type wheel; means for rotating the same; an inking roller coöperating with the type wheel; and mechanism, actuated by the type wheel rotating means, to apply ink to the inking roller.

10. In a printing telegraph receiver, the combination of a type wheel, means for rotating the same, an inking roller coöperating therewith, a movable ink applying member for applying ink to said inking roller, and means for periodically moving said member into coöperative relation with said roller.

11. In a printing telegraph receiver, in combination, a rotatable type wheel; means for rotating the same; an inking roller coöperating with the type wheel; a movable

ink reservoir; mechanism actuated by said means for moving the reservoir toward and from the inking roller at intervals; and means carried by the reservoir to engage the inking roller and apply ink thereto.

12. In a printing telegraph receiver, a type wheel; an inking roller coöperating therewith; a pivotally mounted ink reservoir, adjacent to the roller and having brushes to apply ink to the roller but normally out of contact therewith; an arm mounted on the reservoir; and a revolving finger arranged to engage and actuate the arm at intervals whereby to swing the reservoir and bring the inking brushes into contact with the roller.

In testimony whereof I affix my signature in the presence of two subscribing witnesses.

GEORGE S. HILTZ.
